(57) **CLAIM**

The ornamental design for a sun visor, as shown and described.

DESCRIPTION

FIG. 1 is a front perspective view of a sun visor, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a perspective view showing the sun visor in a use state thereof;

FIG. 10 is a perspective view showing the sun visor in a folded state thereof; and,

FIG. 11 is an enlarged detail view of area 11 in FIG. 1. The thin broken lines in the drawings illustrate the portions of the sun visor, which form no part of the claimed design. The thick broken lines representing stitching are part of the claimed design.

The dash-dot-dash broken lines encircling the enlarged views are for annotative purposes only and form no part of the claim thereof.
